UNITED STATES PATENT OFFICE.

WADE W. MOORE, OF PITTSBURG, CALIFORNIA, ASSIGNOR TO JESSE E. ROACH, OF OAKLAND, CALIFORNIA.

LEAD-PENCIL.

1,369,347.

Specification of Letters Patent. Patented Feb. 22, 1921.

Application filed December 1, 1919. Serial No. 342,022.

To all whom it may concern:

Be it known that I, WADE W. MOORE, a citizen of the United States, residing in the city of Pittsburg, in the county of Contra Costa 5 and State of California, have invented a certain new and useful Improvement in Lead-Pencils, of which the following is a specification.

My invention relates to improvements in 10 lead pencils of the type wherein a permanent body is supplied with extra leads and from which individual leads are projected from the writing point or end of the pencil by suitable mechanism.

15 The primary object of the present invention is to provide a new and improved pencil of the character described having few parts of simple construction, which shall be easily and readily operated.

20 It is also an object of the present invention to provide a new and improved construction which shall be economical and possessed of a maximum efficiency and strength.

25 A further object is to provide a pencil of the type specified wherein the mechanical parts may be quickly operated to renew a lead and project the same from the pencil.

30 A still further object is to provide new and improved means for normally preventing a movement of the lead within the writing point to prevent accidental or inadvertent removal of the lead from the pencil.

Other objects will hereinafter more fully appear.

35 I accomplish these several objects by means of the improved device disclosed in the drawings forming a part of the present specification wherein like characters of reference are used to designate similar parts 40 throughout the said specification and drawings, and in which:

Figure 1 is a broken view of my improved pencil partly in longitudinal section;

45 Fig. 2 is an enlarged transverse sectional view taken on line 2—2 of Fig. 1 in the direction indicated;

Fig. 3 is an enlarged transverse sectional view taken on line 3—3 of Fig. 1 in the direction indicated;

50 Fig. 4 is an enlarged transverse sectional view taken on line 4—4 of Fig. 1 in the direction indicated;

Fig. 5 is an enlarged broken view of the magazine and follower removed from the 55 pencil and shown partly in vertical section;

Fig. 6 is an enlarged view of the hollow core and lead retaining means; and

Fig. 7 is an enlarged transverse sectional view taken on line 7—7 of Fig. 6 in the direction indicated.

60 Referring to the drawings the numeral 1 is used to designate a shell having a plurality of longitudinally disposed grooves 2 on the inner surface thereof and an internal or female thread 3 in one end thereof which 65 is engaged by a male thread on a hollow tapered end 4 provided with an axial bore 6, said tapered end 4 forming a continuation of the shell 1.

70 By means of this novel arrangement a simple and effective barrel or pencil is simply and economically provided. The tapered end may be easily and cheaply produced on a standard screw machine and the shell 1 may be produced of standard tubing. 75 This arrangement eliminates the expensive method of "drawing" a tapered tube from sheet metal and the longitudinally disposed ribs 2 provide a strengthening means to impart strength to said shell, and also to slidably engage a follower in a manner herein-after more fully described.

80 A threaded magazine 7 is arranged to contain extra leads 8 for the pencil and is provided with an exterior thread 9 of comparatively large pitch, the purpose of which will hereinafter be more fully set forth, and a threaded collar 11 immovably mounted on the inner end of the magazine of normal or standard pitch to engage the female thread 90 of the tapered end 4, whereby said magazine 7 may be rotatably mounted within the pencil.

85 The magazine 7 is also provided with a longitudinally disposed radial groove 12 extending throughout the length thereof but having a portion of said groove 12 filled with a solder or the like as at 14 so as to leave an axial bore as a continuation of said groove, the purpose of which will hereinafter be 90 more fully set forth.

95 Screwed upon the thread 9 of the magazine 7 is a follower 16 having a collar 17 thereon provided on its outer surface with a plurality of ribs 18 adapted for slidable engagement with the longitudinal grooves 2 of the shell 1, and said collar is likewise provided with an internal annular groove 19 which is slidably engaged by an arcuate member 21 on the end of a lateral extension 105 110

22 of a longitudinally disposed plunger 23 slidably mounted within the radial groove 12 of the magazine 7, the free end of said plunger 23 being positioned between the 5 filler 14 and the back of the groove 12 as disclosed in Fig. 1 of the drawings.

The end of the magazine 7 is also provided with a standard thread 26 to receive a closing cap 24 having a tubular extension 10 28 to aline the free end of the plunger 23 with the reduced portion 29, open on one side thereof, of a core 31 mounted within the tapered end 4. A spring clamp 32 is clamped upon the reduced portion 29 of the 15 core 31 and extends into said opening to frictionally engage the lead 8 therein to normally prevent movement of said lead within the reduced portion 29.

The upper end of the magazine 7 is provided with an ornamental head or knob 33 extending exteriorly of the shell 1 whereby said magazine 7 may be rotated to operate the follower 16 and the plunger 23. The ornamental head 33 inclosing an eraser element 35 is fully disclosed and described in applicant's co-pending application, Serial No. 342,021, reference to which is hereby made.

In operation a lead 8 is dropped into the 30 shell 1, with the members 7, 16, and 23 removed and the magazine 7 with the follower 16 and plunger 23 positioned therein is then inserted in the shell 1 the follower 16 being then adjacent the knob or head 33.

35 Insertion of the magazine and engagement of the ribs 18 with the grooves 2 of the shell 1 is easily and readily accomplished by reason of the plurality of said ribs and grooves, as it is not necessary that any particular 40 rib should engage any particular groove. A slight clock-wise rotation of the head or knob 33 will rotate the magazine 7 and cause the threads of the collar 11 to engage the female threads of the tapered end 4 thereby in-

45 stantly and rotatably connecting or securing the magazine 7 within the shell 1. As the knob 33 is rotated the follower 16 is moved longitudinally upon the magazine 7 and within the shell 1. Rotation of the follower

50 16 is prevented by the slidable engagement of the ribs 18 of the collar 17, on the said following 16, with the longitudinally disposed grooves 2 of the shell 1. As the follower 16 is moved longitudinally within 55 said shell 1 the annular groove 19 of said collar 17 slidably engages the arcuate member 21 on the lateral extension 22 of the plunger 23 within the radial groove 12 of the magazine 7 and thereby moves said

60 plunger 23 against the lead 8 within the reduced portion 29 of the core 31 whereby said lead 8 may be projected from the writing point of the pencil or the axial bore 6 of the tapered end 4. The relatively greater pitch 65 of the thread 9 causes the follower 16 to be

advanced a greater distance with each revolution of the magazine 7 than the magazine itself is advanced by engagement of the collar 11 with the internal threads of the tip 4. The relative pitch of the two threads 70 is such as to cause the magazine 7 and the follower 16 to be advanced to the extreme positions simultaneously.

The lead 8, being frictionally engaged by the clamp 32, is held within its projected position until broken or worn by usage when an additional portion may be readily and easily projected by the simple expedient of again rotating the knob 33 to actuate the plunger 23. 75

Inasmuch as the clamp 32 engages the lead 8 longitudinally it is obvious that considerable pressure is brought to bear against said lead 8 so that the same is firmly held within the pencil and cannot become lost or 80 inadvertently move out of the pencil.

When a new lead is to be inserted a slight rotation of the knob 33 in a contra-clock-wise direction will move the follower 16 and plunger 23 operatively connected thereto toward said knob 33 and simultaneously disengage or unscrew the threaded collar 11 from the female thread of the tapered end 4, thereby permitting a quick and ready withdrawal of the magazine from the shell 1. 90

The cap 24 is then removed from the inner end of the magazine 7 and a new lead taken from said magazine and inserted within the shell 1 as hereinbefore described. The cap 24 is then replaced and the magazine 7 is 100 then replaced within and operatively connected to the shell 1.

From the foregoing it is obvious that I have provided a new and improved construction for lead pencils wherein a simple, effective and economical structure is obtained having a maximum efficiency. It is also evident that the plurality of ribs 18 and the grooves 2 of the shell 1 provide a new and novel construction whereby slidable engagement of the follower 16 within the shell 1 is easily and quickly obtained. 110

Having thus described my invention, what I claim as new and desire to secure by Letters Patent is:

1. In a lead pencil, the combination of a shell having a plurality of grooves on the inner surface thereof; a threaded magazine rotatably connected at its inner end with the shell and having a longitudinally disposed radial groove therein; a threaded follower screwed upon the magazine and adapted for slidable engagement with the grooves of the shell to prevent rotation of said follower; and a plunger mounted within the longitudinally disposed radial groove of the magazine and operatively connected to the follower whereby said plunger may be longitudinally moved within the pencil when the magazine is rotated. 120 125 130 135 140 145 150 155 160 165 170 175 180 185 190

2. In a lead pencil, the combination of a shell grooved internally; an exteriorly threaded magazine adapted for engagement at its inner end with the interior of the shell; a threaded follower screwed upon the magazine and having longitudinally disposed corrugations thereon to engage the internally grooved shell to prevent rotation of said follower; and a plunger mounted for longitudinal movement within the shell and operatively connected to the follower whereby rotation of the magazine will move said follower and plunger longitudinally within the pencil.
3. In a lead pencil, the combination of a shell grooved internally; an exteriorly threaded magazine adapted for engagement at its inner end with the interior of the shell; a threaded follower screwed upon the magazine and having longitudinally disposed corrugations thereon to engage the internally grooved shell to prevent rotation of said follower; a plunger mounted for longitudinal movement within the shell and operatively connected to the follower whereby rotation of the magazine will move said follower and plunger longitudinally within the pencil; and means for rotating the magazine within the shell.
4. In a lead pencil, the combination of a shell having a plurality of longitudinal grooves on the inner surface thereof; a threaded magazine rotatably mounted within the shell; a follower screw-threaded upon the magazine and adapted for slidable engagement with the grooves of the shell and having an internal annular groove therein; and a plunger mounted for longitudinal movement within the shell and having a lateral extension slidably engaging the annular groove within the follower whereby rotation of the magazine will move the follower and plunger longitudinally within the pencil.
5. In a lead pencil, the combination of a shell having a plurality of longitudinally disposed grooves on the inner surface thereof; a threaded magazine rotatably connected at its inner end within the shell and having a longitudinally disposed radial groove formed therein; a follower screw-threaded upon the magazine and having a plurality of longitudinally disposed ribs to slidably engage the grooves of the shell and also provided with an internal annular groove; and a plunger mounted within the radial groove of the magazine and having a lateral extension slidably engaging the annular groove of the follower whereby said plunger may be moved longitudinally with the follower when the magazine is rotated.
6. In a lead pencil, the combination of a shell having longitudinally disposed grooves on the inner surface thereof; a hollow tapered end screw-threaded to the shell and having an axial bore therein and forming a continuation of said shell; a threaded magazine having its inner end adapted for rotatable engagement with the inner end of the tapered end; a follower screwed upon the magazine and adapted for slidable engagement with the grooves of the shell, whereby said follower may be moved longitudinally within the pencil when the magazine is rotated therein; and a plunger operatively connected to the follower and adapted to move a lead longitudinally through the tapered end when the magazine is rotated.
7. In a lead pencil, the combination of a shell having longitudinally disposed grooves on the inner surface thereof; a hollow tapered end screw-threaded to the shell and having an axial bore therein and forming a continuation of said shell; a threaded magazine having its inner end adapted for rotatable engagement with the inner end of the tapered end; a follower screwed upon the magazine and adapted for slidable engagement with the grooves of the shell, whereby said follower may be moved longitudinally within the pencil when the magazine is rotated therein; a plunger operatively connected to the follower and adapted to move a lead longitudinally through the tapered end when the magazine is rotated; and means for frictionally engaging the lead to normally prevent movement thereof.
8. In a lead pencil, the combination of a shell having longitudinally disposed grooves on the inner surface thereof; a hollow tapered end rigidly connected to one end of the shell and forming a continuation thereof and provided with an axial bore; a threaded magazine adapted at its inner end for rotatable engagement with the inner end of the tapered end and having a longitudinally disposed radial groove formed therein; a follower screwed upon the magazine and having an internal annular groove formed therein and provided with longitudinally disposed ribs to slidably engage the grooves of the shell to prevent rotation of and thereby move said follower longitudinally when the magazine is rotated; and a plunger mounted within the groove of the magazine and having a lateral extension slidably engaging the annular groove within the follower to move said plunger longitudinally against a lead in the bore of the tapered end.
9. In a lead pencil, the combination of a shell having longitudinally disposed grooves on the inner surface thereof; a hollow tapered end rigidly connected to one end of the shell and forming a continuation thereof and provided with an axial bore; a threaded magazine adapted at its inner end for rotatable engagement with the in-

ner end of the tapered end and having a longitudinally disposed radial groove formed therein; a follower screwed upon the magazine and having an internal annular groove 5 formed therein and provided with longitudinally disposed ribs to slidably engage the grooves of the shell to prevent rotation of and thereby move said follower longitudinally when the magazine is rotated; a plunger 10 mounted within the groove of the magazine and having a lateral extension slidably engaging the annular groove within the follower to move said plunger longitudinally against a lead in the bore of the tapered end; and means for frictionally engaging said lead to normally prevent movement thereof within said bore.

10. In a lead pencil, the combination of a shell grooved longitudinally on the inner surface thereof; a hollow tapered end connected to one end of the shell to form a continuation thereof and having an axial bore therein; a threaded magazine mounted within the shell and adapted to rotatably 25 engage the tapered end, a follower screwed upon the magazine and slidably engaging the longitudinal grooves in the shell to prevent rotation of said follower; and a plunger operatively connected to the follower 30 and adapted to be actuated by said follower to move a lead longitudinally through the pencil and bore of the tapered end when the magazine is rotated.

11. In a lead pencil, the combination of a shell grooved longitudinally on the inner surface thereof; a hollow tapered end connected to one end of the shell to form a continuation thereof and having an axial bore therein; a threaded magazine mounted within the shell and adapted to rotatably engage 40 the tapered end, a follower screwed upon the magazine and slidably engaging the longitudinal grooves in the shell to prevent rotation of said follower; a plunger operatively connected to the follower and adapted to be actuated by said follower to move a lead longitudinally through the pencil and bore of the tapered end when the magazine is rotated; and means for frictionally engaging 45 said lead to normally prevent movement thereof through said bore.

12. In a lead pencil, the combination of a shell grooved longitudinally on the inner surface thereof; a hollow tapered end connected to one end of the shell to form a continuation thereof and having an axial bore therein; a threaded magazine mounted within the shell and adapted to rotatably engage the tapered end, a follower screwed 60 upon the magazine and slidably engaging the longitudinal grooves in the shell to prevent rotation of said follower; a plunger operatively connected to the follower and adapted to be actuated by said follower to 65 move a lead longitudinally through the pen-

cil and bore and tapered end when the magazine is rotated; means for frictionally engaging said lead to normally prevent movement thereof through said bore; and a guide secured to the end of the magazine and adapted to retain the free end of the plunger coaxial with the pencil and to close the magazine.

13. In a lead pencil, the combination of a shell having a plurality of longitudinally disposed grooves in the inner surface thereof; a hollow tapered end mounted upon one end of the shell and forming a continuation thereof, said tapered end having an axial bore, and an internal thread therein; a magazine arranged to contain extra leads for the pencil and having one thread thereon of comparatively large pitch and smaller normally pitched thread to engage the internal thread in the hollow tapered end, and provided with a longitudinally disposed radial groove; a follower screwed upon the magazine thread of larger pitch and arranged for slidable engagement with the grooves of the shell; and a plunger mounted within the radial groove of the magazine and operatively connected with the follower and adapted to be moved by said follower when the magazine is rotated to move a lead longitudinally through said bore of said tapered end.

14. In a lead pencil, the combination of a shell having a plurality of longitudinally disposed grooves in the inner surface thereof; a hollow tapered end mounted upon one end of the shell and forming a continuation thereof, said tapered end having an axial bore and an internal thread therein; a magazine arranged to contain extra leads for the pencil and having one thread arranged thereon of comparatively large pitch and a smaller normally pitched thread to engage the internal thread in the hollow tapered end, and provided with a longitudinally disposed radial groove; a follower screwed upon the magazine thread of larger pitch and arranged for slidable engagement with the grooves of the shell; a plunger mounted within the radial groove of the magazine and operatively connected with the follower and adapted to be moved by said follower when the magazine is rotated to move a lead longitudinally through said bore of said tapered end; and means mounted within the hollow tapered end for frictionally engaging said lead to normally prevent movement thereof.

15. In a lead pencil, the combination of a shell having a plurality of longitudinally disposed grooves on the inner surface thereof; a hollow tapered end mounted upon one end of the shell and forming a continuation thereof, said tapered end having an axial bore and an internal thread therein; a magazine arranged to contain extra leads

- for the pencil and having one thread thereon of comparatively large pitch and a smaller normally pitched thread to engage the internal thread in the hollow end, 5 and provided with a longitudinally disposed radial groove; a follower screwed upon the magazine thread of larger pitch and arranged for slidable engagement with the grooves of the shell; a plunger mounted 10 within the radial groove of the magazine and operatively connected with the follower and adapted to be moved by said follower when the magazine is rotated to move a lead longitudinally through said bore of said 15 tapered end; a hollow core mounted within the tapered end and having a reduced cylindrical portion open on one side thereof; and a spring clamp mounted upon said reduced portion and adapted to extend through said 20 opening and frictionally engage a lead thereon to normally prevent movement of said lead within said reduced portion.
16. In a lead pencil, the combination of a shell having a plurality of grooves on the inner surface thereof; a hollow tapered end secured to one end of the shell and having an internal thread and an axial bore; a threaded magazine mounted within the shell and having a longitudinally disposed radial 25 groove formed therein; a follower screwed upon the magazine and arranged to slidably engage the grooves within the shell; a plunger mounted within the radial groove of the magazine and operatively connected to the 30 follower whereby said plunger may be actuated to move a lead longitudinally through the axial bore of the tapered end when the magazine is rotated; and a guide detachably connected to the open end of the magazine 35 and adapted to engage the free end of the plunger and retain the same in alinement with the axial bore of the tapered end and to engage the internal thread of the tapered 40 end to rotatably retain the magazine within the shell; a hollow core within the tapered 45 end having a reduced cylindrical portion open on one side thereof; and a spring clamp mounted upon said reduced end and extending into the open portion of said cylindrical portion to frictionally engage a lead therein 50 to normally prevent movement of said lead within said bore.
17. In a lead pencil, the combination of a shell having a plurality of grooves on the inner surface thereof; a hollow tapered end secured to one end of the shell and having an 55 internal thread and an axial bore; a threaded magazine mounted within the shell and having a longitudinally disposed radial groove formed therein; a follower screwed upon 60
- the magazine and arranged to slidably engage the grooves within the shell; a plunger 55 mounted within the radial groove of the magazine and operatively connected to the follower whereby said plunger may be actuated to move a lead longitudinally through the axial bore of the tapered end when the 60 magazine is rotated; a guide detachably connected to the open end of the magazine and adapted to engage the free end of the plunger and retain the same in alinement with the axial bore of the tapered end and to 65 engage the internal thread of the tapered end to rotatably retain the magazine within the shell; and means mounted within the hollow tapered end and arranged to frictionally engage a lead in the bore of said 70 end to normally prevent movement of said lead within said bore.
18. In a lead pencil, the combination of a shell having a plurality of grooves on the inner surface thereof; a hollow tapered end 75 secured to one end of the shell and having an internal thread and an axial bore; a threaded magazine mounted within the shell and having a longitudinally disposed radial groove formed therein; a follower screwed 80 upon the magazine and arranged to slidably engage the grooves within the shell; a plunger mounted within the radial groove of the magazine and operatively connected to the follower whereby said plunger may be actuated to move a lead longitudinally through the axial bore of the tapered end when the magazine is rotated; a guide detachably connected to the open end of the magazine and 85 adapted to engage the free end of the plunger and retain the same in alinement with the axial bore of the tapered end and to engage the internal thread of the tapered end to rotatably retain the magazine within the shell; a hollow core within the tapered 90 end having a reduced cylindrical portion open on one side thereof; and a spring clamp mounted upon said reduced end and extending into the open portion of said cylindrical portion to frictionally engage a lead therein 100 to normally prevent movement of said lead within said bore.

In witness whereof I hereunto set my signature.

WADE W. MOORE.
